UNITED STATES PATENT OFFICE.

WILLIAM C. FREE, OF CHICAGO, ILLINOIS.

TAKE-UP FOR SEWING-MACHINES.

SPECIFICATION forming part of Letters Patent No. 699,678, dated May 13, 1902.

Application filed October 21, 1901. Serial No. 79,475. (No model.)

To all whom it may concern:

Be it known that I, WILLIAM C. FREE, a citizen of the United States of America, residing at Chicago, in the county of Cook and State of Illinois, have invented certain new and useful Improvements in Take-Ups for Sewing-Machines, of which the following is a specification.

This invention relates specifically to improvements in take-up mechanisms for sewing-machines.

The object of these improvements is to provide a take-up mechanism that will automatically regulate the needle-thread of a sewing-machine so that a greater or lesser amount thereof will be furnished to its needle, according as such machine is sewing together thick, medium, or thin fabrics; and they consist of certain new and useful features of construction and combinations of parts especially constructed and designed to that end, all as hereinafter fully described, and specifically pointed out in the claims.

Referring to the accompanying drawings, which form a part of this specification, Figures 1, 2, 3, and 4 are isometrical views of the terminal head on the free end of the sewing-machine arm and its shuttle. Fig. 5 is a front elevation of the same with the face-plate thereof removed. Fig. 6 is a section at the line 6 6 in Fig. 5 of parts there shown. Fig. 7 is a front elevation of parts shown in Fig. 5 and illustrates their modes of operation. Fig. 8 is a section at the line 8 8 in Fig. 7 of parts there shown. Fig. 9 is a side elevation of a fragment of the free end of the arm of the machine and its terminal head broken away to show parts within. Figs. 10 and 11 are detailed views of parts shown in Fig. 9 with other parts added.

The foregoing views fully illustrate and embody my improvement. They do not, however, show the arm in its entirety, its supporting-post, the entire driving-shaft and its bearings, and mechanism for rotating the former, as they are not essential to a complete understanding of my invention. No further reference will therefore be made hereinafter to the fact that such parts are not shown in the drawings or that they are fragmental.

Like letters of reference indicate corresponding parts throughout the several views.

A is the terminal head on the free end of the arm A' and will be hereinafter referred to by the term "head" only. The head A 55 has a recess A² therein, Fig. 5, ordinarily rectangular in form, as here shown, and formed by integral walls A³, A⁴, A⁵, A⁶, and A⁷ and closed by a removable face-plate A⁸.

B is a driving-shaft mounted horizontally 60 in bearings in the post and arm of the machine.

C is a wrist-wheel fast to the driving-shaft B, provided with an outwardly-extending wrist C' and having a circumferential groove 65 C² therein adapted to engage and operate a take-up lever to be described hereinafter.

D is a take-up lever engaged at one end D' by the circumferential groove C² in the wrist-wheel C and provided at its other end 70 D² with a thread-eye D³ and mounted, by means of the pivot D⁴ on the lug D⁵, on the interior of the arm A'.

E is a vertically-movable presser-bar mounted in bearings E' E² in the walls A⁶ A⁷ 75 of the head A and terminating at its lower end E³ in a presser-foot E⁴ of the ordinary form.

F is a bracket fast to the presser-bar E by being passed through and secured in the opening F' therein and arranged to reciprocate 80 vertically therewith and also having a slide-way F², Fig. 8, therein to admit the vertical guide-stud F³, projecting from the wall A⁷ of the head A, which serves to prevent lateral vibration of the end F⁴ of the same. 85

G is a tubular bearing rigidly secured, by means of a screw G', to the vertical lug G², projecting from and integral with the bracket F.

H is a slack-thread-controlling lever provided at its free end H' with a thread-eye H² 90 and mounted on the bearing G on the bracket F by means of the spring H³, fast by its other end H⁴ to and coiled about said bearing G, which is integral and continuous with and actuates said slack-thread-controlling lever H. 95

H⁵ is a shield covering the front upper portions of the spring H³ and its bearing G and having a vertical slot H⁶, Fig. 6, therein serving as a stop to limit the upward and downward movements of the free end H' of the 100 slack-thread-controlling lever H.

I is a threaded spindle inserted by tapping through an opening I³ in the front wall A⁴ of the head A.

J J' are a pair of perforated disks loosely mounted on the spindle I and having convex opposing faces J² J³, and the latter, J', being providing with a releasing-lever J⁴.

5 L is a spiral spring normally holding the disks J J' in contact and is retained in position and adjusted on the spindle I by means of a nut L'.

O is a spring normally impelling the presser-bar E and its presser-foot E⁴ downward, as in Fig. 1.

P is a cam-lever mounted on the pivot-bearing P' for raising the bracket F, the presser-bar E, and its presser-foot E⁴ against 15 the action of the spring O.

Q, Fig. 5, is a needle-bar mounted in the usual manner in bearings Q' Q³ in the walls A⁶ A⁷ of the head A and provided at its lower end with a needle Q³. The needle-bar 20 Q is connected with the wrist C' on the wrist-wheel C by means of the slot Q⁴ in the inner face of the cross-head Q⁵, through which said needle-bar Q is inserted and to which it is fast.

25 Fig. 1 shows the machine just as the needle Q³ has finished its upward course and just as the take-up lever D² has finished its upward stroke and drawn the needle-thread R tautly upward against the under side of the shuttle-thread S to finish a stitch. While the take-up lever D² was traveling upward to tighten the thread R the latter also drew the free end of the slack-thread controlling-lever H upward against the action of its spring H³ a 30 half-inch, more or less, and retained it there by frictional contact therewith. The resistance offered by the spring H³ of the slack-thread-controlling lever H obviously assisted the take-up lever D² in tightening the thread 35 R to complete the stitch last finished.

40 Fig. 2 shows the needle Q³ just as its point is entering the cloth T. It will be there observed that the take-up lever D² and the slack-thread - controlling lever H have both descended a little distance from the positions 45 they occupied in Fig. 1 and that the resiliency of the spring H³ of the slack-thread-controlling lever H has caused the latter to descend sufficiently to take up the slack of the thread 50 R caused by the descent of the take-up lever D², and thereby prevented the slack portion of said thread R from passing downward below the point of the needle Q³ and being either entangled or sewed down thereby, or both.

55 Fig. 3 shows the needle Q³ after it has completed its downward course, the take-up lever D² and the slack-thread-controlling lever H also having descended to their lower limit of travel, the latter having been impelled by 60 the action of its spring H³ to a still further descent from the position shown in Fig. 2 in order to completely release that portion of the thread R extending from the friction-disks J J' to the needle Q³, and thereby permit it 65 to be available to form a loop R' of sufficient size to admit of the passage therethrough of the shuttle S'.

Fig. 4 shows the take-up lever D² and the slack-thread-controlling lever H taking up the slack thread R (shown in Fig. 3) after the 70 shuttle S' has passed through the loop formed thereby and returning simultaneously with the return of the needle Q³ to the positions shown in Fig. 1 to complete a stitch.

Since the slack-thread-controlling lever H 75 and its spring H³ are mounted on the bearing G, rigidly connected through the bracket F with the presser-bar E, it is evident that the distance between the presser-foot E⁴ thereon and such slack-thread-controlling lever H will 80 always remain the same. As a result thereof the slack-thread-controlling lever H will travel up and down simultaneously with the presser-foot E⁴ and, regulated by the action 85 of its spring H³, will in turn automatically 90 regulate the thread R by causing it to be paid out to the needle Q³ in amounts corresponding with the varying thicknesses of the material being sewed, whether the same be very thin, medium, or very thick, for when 95 the presser-foot E⁴ is raised—as, for instance, by a thick seam or welt passing thereunder at right angles thereto—the slack-thread-controlling lever H will also be raised a corresponding distance and as a result take 100 up less of the thread R, thus leaving more of it at the disposal of the needle Q³ to supply the suddenly and temporarily increased demand therefor. Obviously when 105 the presser-foot E⁴ descends from the seam 110 or welt to a lower position the slack-thread-controlling lever H will descend a corresponding distance and take up more of the thread 115 R, leaving less at the disposal of the needle Q³. As the net result of all of which it will 120 be seen that the take-up mechanism of the machine automatically regulates the needle-thread R, so as to adapt it to sew together fabrics of any desired thickness within the 125 limits of the travel of the presser-foot E⁴. 130

Fig. 7 shows the bracket F and presser-bar E in their lower positions and the spring O acting to maintain them there and the presser-foot E⁴, Fig. 1, in operative contact with the work T. With the parts of the tension mechanism of the machine in the position shown in Figs. 1 and 7 the tension of the thread R may be regulated by means of the nut J'. Whenever it is desired to remove the work T from the machine, the cam-lever P is elevated from the position shown in Fig. 7 to that shown in Fig. 5, with the result that the cam-surface P² thereon engaged and elevated the bracket F and the presser-bar E and its foot E⁴, carried thereby, from the positions shown 125 in said Fig. 7 to those shown in said Fig. 5, when by pressing upon the releasing-lever J⁴, Fig. 5, the thread R will be released from the friction-disks J J' and such work T may be removed from the machine.

What I claim as new, and desire to secure by Letters Patent, is—

1. In a take-up mechanism for sewing-machines, in combination, a take-up lever pro-

vided with a thread-eye, a vertically-movable presser-bar, a bracket fast to the presser-bar and arranged to reciprocate vertically therewith, a slack-thread-controlling lever, mounted on the bracket on the presser-bar and provided, at its free end, with a thread-eye, means for actuating the take-up lever and means for reciprocating the presser-bar, substantially as and for the purpose specified.

5 2. In a take-up mechanism for sewing-machines, in combination, a driving-shaft, a wheel—fast thereto—having a circumferential cam-groove therein adapted to engage and operate a take-up lever, a take-up lever engaged, at one end, by the circumferential groove in the wheel, and provided, at its other end, with a thread-eye, a vertically-movable

presser-bar, a bracket fast to the presser-bar and arranged to reciprocate vertically therewith, a slack-thread spring-actuated controlling-lever mounted on the bracket on the presser-bar and provided, at its free end, with a thread-eye, and bearings, in the machine-frame, for operatively supporting all of said parts, substantially as and for the purpose 25 specified.

In testimony whereof I have signed my name to this specification in the presence of two subscribing witnesses.

WILLIAM C. FREE.
